METHOD OF FORMING ABRASIVE ARTICLES

Frederick K. Bezzenger, Cleveland Heights,
Ohio, assignor to The Stratmore Company,
Cleveland, Ohio, a corporation of Ohio

Application January 4, 1933, Serial No. 650,096

18 Claims. (Cl. 51—278)

The present invention relates to a method of forming abrasive articles and, more particularly, to an improved method of making sandpaper, and the like.

5 Ordinary sandpaper has heretofore been made by coating a sheet of paper with glue, sprinkling particles of abrasive such as garnet, silicon carbide, and the like thereon, and then rolling the abrasive particles into the glue in order to secure 10 a sufficient bond between the particles and the glue to retain the former on the paper in use. Sometimes a sizing layer of thin glue is applied after the rolling operation, covering exposed surfaces of the particles in order further to insure 15 that the particles will remain in place. Sandpaper as so made is not uniform since the abrasive particles cannot be sprinkled evenly over the surface of the paper and are found to be more concentrated in some spots than in others, with the 20 result that some of the particles are not securely glued to the paper and may be readily brushed off before or during use. Another objection to such paper is that the particles are pressed so far into the glue by the subsequent rolling that a large 25 portion of the particle is submerged in the glue and not available for abrading purposes with the result that the sandpaper is used up and must be discarded long before any considerable proportion of the particle body is consumed. The 30 sizing glue placed over the particles also accelerates the consumption of the sandpaper since this glue becomes hot, due to friction between the sheet and the work, and flows down between the particles, where it retains ground-off material and 35 builds up to load and mask the abrasive particles.

It has also been the practice to prepare sandpaper and the like with the abrasive particles distributed over the entire surface of the sheet, no special provision being made to prevent loading, 40 the paper then being used until the particles wear down and the paper loads up with ground-off material to prevent further abrasive action. The paper must then be discarded even though the abrasive particles themselves are still largely un- 45 worn.

By the method herein to be described, the foregoing objections are largely overcome by distributing the abrasive particles more nearly uniformly over the glued surface of a sheet and by applying 50 the particles to the glue with just the right amount of pressure to insure a firm bond between the paper and the abrasive particles, but without embedding the particles in the glue to an excessive degree such as would shorten the life of the paper 55 and without the need of applying a sizing coat of

glue which would accelerate the loading of the paper with the same effect.

It is, accordingly, an object of the present invention to provide a method of making an abrasive article which results in a sandpaper having 5 a longer effective working life than that now in use. Another object of the invention is to provide a method of making sandpaper and similar abrasive sheets in which the force with which the abrasive particles are applied to a glue surface 10 can be regulated at will. A further object of the invention is to provide a method of making abrasive elements in which the abrasive particles can be distributed over a sheet with greater uniformity, and with a greater proportion of their cutting 15 surfaces and of their volume exposed above the glue line. Still another object of the invention is to provide a method of making abrasive elements which is more convenient and quicker than those now in use. A still further object is to provide 20 a method of making abrasive elements in which a rolling operation rolling the abrasive particles down into the glue is avoided and in which the application of a sizing coat over the rolled-in particles is not necessary. And still another object of the invention is to provide a 25 method of making abrasive articles whereby the abrasive may be applied to its base in discontinuous areas separated by areas free of abrasive. To the accomplishment of the foregoing and related 30 ends, said invention, then, consists of the steps hereinafter fully described and particularly pointed out in the claims.

The annexed drawings and the following description set forth in detail one approved method 35 of carrying out the invention, such disclosed method however, constituting but one of the various ways in which the principle of the invention may be used.

In said annexed drawings:

Fig. 1 is a diagrammatic view, partly in section, of an apparatus which may be used to carry out the disclosed method; Figs. 2 and 3 are side views of alternative elements which may be used in the apparatus shown in Fig. 1; Fig. 4 is a 45 transverse section taken along the line 4—4 of Fig. 3; Figs. 5 and 6 are fragmentary views of abrasive articles prepared by the use of the elements shown in Figs. 2 and 3 respectively; Fig. 7 is a fragmentary view of an abrasive article prepared by the 50 use of the apparatus shown in Fig. 1; and Fig. 8 is a sectional elevation of a type of abrasive article as shown in Fig. 5.

In the drawings, a quantity of abrasive particles 55 such as garnet or silicon carbide, is placed in a

trough or other container 2 in which revolves a roller 3. This roller cooperates with a second roller 4 placed directly above it, the two rollers being provided with adjusting means, such as a turnbuckle 5, for regulating the distance therebetween. The roller 3 may be of iron or any other suitable material and is provided with a surface 6 of some material having limited adhesive powers such as the glue and glycerine compositions used in printer's platen rollers. The composition of this surface may be varied provided that its adhesive power is less than that of warm or soft glue, as will appear hereinafter.

The roller 3 is caused to revolve in the trough 2 and picks up on the surface 6 a layer 7 of abrasive particles which are brought up into contact with a sheet 8 of paper or other material which is to be coated with abrasive. This sheet travels from a supply roll past glue-coating means over a heated roller 9 which is revolved adjacent the glued surface 11 of the sheet in order to bring this glue to such a temperature that it will readily retain abrasive particles brought in contact therewith. The sheet then passes between the rolls 3 and 4 which are so adjusted by means of the turnbuckle 5 that the abrasive particles 7 are pressed into the glue surface 11 as the sheet 8 passes therebetween. The sheet then continues its travel with a layer of abrasive 12 thereon and the glue may then be quickly set by passing the sheet under a heated roller 13 which contacts the back of the sheet.

As will be apparent, any desired adjustment of the space between the rollers 3 and 4 may be secured by means of the turnbuckle 5 so that the abrasive particles 7 which are brought upwardly into contact with the glued sheet 8 can be pressed into the glue a greater or less distance as desired. A few tests will quickly determine how far the abrasive particles must be pressed into the glue in order that they will be retained firmly when the finished sheet is used for abrasive purposes and this amount will then not be exceeded so that a maximum proportion of each abrasive particle is left above the glue surface to do its work as a cutting agent in an abrasive operation. The abrasive particles will be readily transferred from the surface of the roller 3 to the surface of the glued sheet because the surface of this roller is purposely prepared with a degree of adhesiveness less than that of the glued sheet. Adjustments between the two surfaces may be made by altering the composition and the temperature of the surface of the roller 3 and also by heating the glued surface 11 by means of the roller 9 to the exact degree of softness desired. Thus the abrasive particles on the roller 3 are immediately removed by the glued sheet upon contact, the glued sheet passing onward with its coating of abrasive and the roller picking up a new layer of abrasive from the trough 2.

Due to the limited adhesive power of the surface of the roller 3, this surface will pick up abrasive particles uniformly over its entire area and, since it has a relatively smooth even surface, it will pick up but one layer of particles with little or no tendency to pile one particle on top of another. When this uniform layer of particles is, in turn, transferred to the glued sheet 8, the particles are transferred in a uniform relation and an abrasive article having its abrasive particles uniformly distributed results. This is an effect not heretofore obtainable due to the fact that the abrasive particles have been directly sprinkled upon the glued sheet with the result that the

distribution was not uniform and there was a considerable tendency for particles to rest on top of others.

The above described method results in an improved abrasive article in which the abrasive is uniformly distributed over the entire surface of a sheet, but the present invention also contemplates a method of preparing sandpaper and the like in which the abrasive is distributed according to a determined pattern, some areas of the sheet being covered with abrasive and other areas being left free of abrasive. Where it is desired to prepare a sheet such as that shown in Fig. 5 having diagonally disposed strips 14 covered with abrasive and alternating with strips 15 left free of abrasive, the roller 16 shown in Fig. 2 may be used. This roller has lands 17 alternating with grooves 18 in which a glue and glycerine composition 19 of limited adhesive power may be disposed. When this roller is brought in contact with a supply of abrasive particles, only the adhesive surfaces will pick up abrasive, and this will, in turn, be transferred in a definite pattern to the paper or other base of the abrasive article, as shown in Fig. 5.

The abrasive may be distributed on the base in any desired pattern, another modification of the apparatus being illustrated in Fig. 3 in which the roller 21 is provided with circular pits or recesses 22 carrying the adhesive compound of limited adhesive power. The use of this roller results in an abrasive article having the pattern shown in Fig. 6 in which the paper 23 carries circular areas 24 covered with abrasive and separated by intervening areas 25 not so covered.

The abrasive distributed in the above described patterns is deposited in accordance with the method herein set forth, the abrasive particles being uniformly distributed within the covered areas and each of the particles projecting above the glue line approximately one-half or more. Where the abrasive is not distributed according to a pattern, it will be uniformly disposed over the entire surface of the base as on the sheet 26 shown in Fig. 7. The invention contemplates the use of the improved method to prepare abrasive articles according to any of the patterns described or according to other patterns which will readily suggest themselves.

From the foregoing description it will be evident that my improved abrasive sheet presents various important advantages, including even and uniform distribution of the abrasive particles, distribution of these particles in any predetermined pattern or arrangement that is desired, the formation of large or small clearance spaces between the grains, the firm individual setting of the grains in the adhesive, permitting the use of a thinner layer of adhesive and hence a greater exposure of the grain with the same or firmer attachment to the backing, a greater sharpness and hence a greater cutting effect of the grains due to their greater exposure, and due also to the absence of any film of adhesive over the exposed surfaces of the grains.

My improved method presents various important advantages including the firm and rapid selective setting of the abrasive grains in the coating of adhesive on the back, and by the method described it is possible to secure a much more even and uniform mounting of the individual more or less irregular particles in the adhesive than by former methods.

Other modes of applying the principle of my invention may be employed instead of the one explained, change being made as regards the meth-

od herein disclosed, provided the step or steps stated by any of the following claims or the equivalent of such stated step or steps be employed.

5 I therefore particularly point out and distinctly claim as my invention:

1. A method of manufacturing an abrasive article which comprises depositing abrasive particles on a surface and bringing said particles in contact with another surface having a greater adhesive power than said first-named surface.

10 2. A method of making an abrasive article which comprises distributing individual abrasive particles over a surface having limited adhesive power to retain the same thereon, and then bringing said surface in close proximity to another surface having greater adhesive power than said first-named surface to transfer said abrasive particles to the other surface.

15 3. A method of manufacturing an abrasive article which comprises depositing abrasive particles onto a surface and bringing said particles while so deposited in contact with another surface having a greater adhesive power than said first-named surface to transfer said abrasive particles to said other surface.

20 4. A method of making an abrasive article which comprises applying a surface having limited adhesive power to a mass of loose abrasive particles, picking up a uniform layer of said particles on said surface, and then bringing said surface with its coating of abrasive particles into contact with another surface having greater adhesive power than said first-named surface to transfer said particles permanently to said other surface.

25 5. A method of making an abrasive article which comprises applying a surface having approximately the adhesive power of a printer's platen roll to a mass of loose abrasive particles, picking up a layer of said particles on said surface and removing said particles from said surface by means of a surface having greater adhesive power than said first-named surface.

30 6. A method of making an abrasive article which comprises revolving a roll having a surface of limited adhesive power in contact with loose abrasive particles, picking up said abrasive particles on said roll, passing a surface having greater adhesive power than said roll in contact with the abrasive particles on said roll, removing said particles from said roll and retaining the same on said surface of greater adhesive power.

35 7. A method of making an abrasive article which comprises revolving a roller having approximately the adhesive power of a printer's platen roll in contact with loose abrasive particles, picking up a layer of abrasive particles on said roller, passing the coated roller in contact with a glued sheet and transferring the abrasive particles to said sheet.

40 8. A method of making an abrasive article which comprises revolving a roller having a glue and glycerine surface in contact with loose abrasive particles, picking up a layer of abrasive particles on the surface of said roller, passing the coated roll in contact with a travelling sheet covered with soft glue, and printing said abrasive particles on said sheet.

45 9. A method of making an abrasive article which comprises passing a sheet coated with softened glue over a roller carrying abrasive par-

ticles in a medium having less adhesion for said particles than said softened glue.

10 10. A method of making an abrasive article which comprises transferring abrasive particles from a pile of the loose particles to a surface coated with warm glue by means of an intermediate surface having sufficient adhesive power to pick up the particles but less adhesive power than said warm glue.

15 11. A method of making an abrasive article which comprises collecting abrasive particles on a surface having limited adhesive power and transferring said particles in a prearranged pattern to a base having greater adhesive power than said first named surface.

15 12. A method of making an abrasive article which comprises collecting abrasive particles on a surface having discontinuous areas with limited adhesive power and other areas with no adhesive power, bringing said surface in contact with another surface having greater adhesive power than said discontinuous areas, and transferring said abrasive particles to said other surface.

20 13. A method of making an abrasive article which comprises collecting abrasive particles on a roller having portions of its surface provided with a material of limited adhesive power, bringing the surface of said roller into contact with a sheet provided with adhesive of greater adhesive power than the material on said roller, and transferring said abrasive to said sheet in a pattern determined by the adhesive portions of the surface of said roller.

25 14. A method of making an abrasive article which comprises picking up abrasive particles on the surface of a roller having portions of its surface provided with a glue and glycerine composition of limited adhesive power, bringing the surface of said roller into contact with a travelling sheet of fibrous material provided with unset glue, and transferring said abrasive particles to said sheet in discontinuous areas corresponding to the adhesive portions of the surface of said roller.

30 15. A method of making an abrasive article which comprises the steps of depositing abrasive particles on a surface in a uniformly distributed and uniform depth layer, moving said surface into proximity with an adhesive surface and then transferring said particles to said adhesive surface.

35 16. A method of making an abrasive article which comprises the steps of depositing abrasive particles on a surface in a uniformly distributed and uniform depth layer, moving said surface while said particles are so deposited into proximity with an adhesive surface and then transferring said particles to said adhesive surface.

40 17. A method of making an abrasive article which comprises the steps of depositing abrasive particles on a surface in a uniformly distributed and uniform depth layer, moving said surface into proximity with an adhesive surface and then transferring said particles in predetermined location to said adhesive surface.

45 18. A method of making an abrasive article which comprises the steps of depositing abrasive particles on a surface in a uniformly distributed and uniform depth layer, moving said surface into proximity with and underneath an adhesive surface and then transferring said particles to said adhesive surface.
